UNITED STATES PATENT OFFICE

140,643

DESIGN FOR A DRINKING GLASS OR SIMILAR ARTICLE

John Pertz, Weston, W. Va., assignor to West Virginia Glass Specialty Company, Incorporated, Weston, W. Va., a corporation of West Virginia

Application November 24, 1944, Serial No. 116,515

Term of patent 7 years

(Cl. D36—8)

To all whom it may concern:

Be it known that I, John Pertz, a citizen of the United States, residing at Weston, in the county of Lewis and State of West Virginia, have invented a new, original, and ornamental Design for a Drinking Glass or Similar Article, of which the following is a specification, reference being had to the accompanying drawing, forming part thereof, in which:

Fig. 1 is an elevational view of the drinking glass or similar article showing my new design; Fig. 2 is a central, vertical section thereof; and, Fig. 3 is a perspective view of the same.

I claim:

The ornamental design for a drinking glass or similar article, substantially as shown.

JOHN PERTZ.
